Primary Examiner—Gary D. Watson
Attorney, Agent, or Firm—Arnold, White & Durkee[57] CLAIM

The ornamental design for a headboard for a seat for a glider or swing, as shown and described.

DESCRIPTION

FIG. 1 is a front perspective view of the headboard for a seat for a glider or swing showing our new design;

FIG. 2 is a front elevational view;

FIG. 3 is a top plan view; and

FIG. 4 is an end elevational view, the opposite end being a mirror image thereof;

FIG. 5 is a rear elevational view; and,

FIG. 6 is a bottom plan view thereof.

The broken lines shown in FIG. 1 are for environmental purposes only and form no part of the claimed design.

FIGS. 2 through 6 have been shown on an enlarged scale.
